UNITED STATES PATENT OFFICE.

LOUIS BUSHMAN, OF TOLEDO, OHIO.

COMB-BRUSH.

Application filed February 29, 1928. Serial No. 257,843.

My invention relates to a new and useful improvement in a comb brush used for combing or brushing the hair, and has for its object the provision of a device which will combine in one article the functions of both a comb and a hair brush.

Another object of the invention is the provision of a device of this class which will be simple in structure, economical of manufacture, and highly efficient in use.

Another object of the invention is the provision of a back or holding member in which a plurality of combs may be mounted in spaced relation.

Another object of the invention is the provision of a holding device for retaining the combs in spaced relation in the back or holder.

Other objects will appear hereinafter.

The invention consists in the combination and arrangement of parts hereinafter described and claimed.

The invention will be best understood by a reference to the accompanying drawings which form a part of this specification and in which,

Fig. 1 is a perspective view of the invention.

Fig. 2 is a view taken on line 2—2 of Fig. 1.

Fig. 3 is a sectional view taken on line 3—3 of Fig. 2.

Fig. 4 is a sectional view taken on line 4—4 of Fig. 2.

The device comprises a handle or back forming portion 7 which is provided with the recess 8 extending substantially from end to end thereof. Communicating with a recess 8 is a recess 9 extending well inwardly of the body of the back 7. The comb and brush unit is formed from a number of independent combs or teeth bearing members so that when the teeth on one of the members becomes broken, this member may be removed and replaced without necessitating the discarding of all of the other members. In the drawings I have illustrated six of these combs although the actual number used depends upon the size of the comb and the size of the back or handle 7.

The comb 10 is provided with a metallic eyelet 11 having the opening formed therein threaded. The end comb 12 is also provided with a collar or eyelet 13 having a threaded passage therein. Collars 14 serve to space the intermediate combs 15 from each other. A carrying member 16 serves to space the centrally positioned combs apart, the screw 17

being projected through these collars and through the holding member 16 and threaded into the eyelet 13 and the eyelet 11 so as to securely bind the combs together into a single 60 unit.

As shown in Fig. 2, three sets of spacers have been used in the present form illustrated. The member 16 is provided intermediate its ends with the offset portion or projection 18 65 adapted to engage snugly in the recess 9 so that when the backs of the combs engage the bottom of the recess 8, the edge of the projection 18 will engage the bottom of the recess 9. This member 16 with its projection 18 is 70 preferably made of metal and is provided with threaded openings for the reception of the screws 19 and 20 which are projected through the side walls of the back 7 into these openings as shown clearly in Fig. 2. 75

The engagement of the projection 18 in the recess 9 serves to prevent tilting or rocking of the comb unit in the holder, and the engagement of the side walls of the holder with the sides of the comb unit serve to hold it in firm 80 position. The screws 17, it will be noted, terminate flush with the outer surfaces of the end of the outer combs 10 and 12 so that no projections are present to interfere with the firm or snug resting of the comb unit in the 85 recess 8.

It is believed obvious that damage to one of the combs would not require that the entire unit be discarded as either of the combs may be removed and replaced at will, it being but 90 necessary to remove the screws 19 and 20 in order to remove the unit from the back or holder.

While I have illustrated and described the preferred form of my invention, I do not wish 95 to limit myself to the precise details of structure shown but desire to avail myself of such variations and modifications as may come within the scope of the appended claims.

Having thus described my invention what 100 I claim as new and desire to secure by Letters Patent is:

1. A device of the class described, comprising: a holder having a recess; a plurality of combs; means for mounting said combs in 105 parallel relation; means for spacing said combs from each other; a securing member positioned between a pair of said combs and secured thereto; a projection on said securing member adapted for engagement in a recess formed in said holding member; and means on said holding member for engaging 110

said projection and securing said combs on said holding member.

2. In a device of the class described, a plurality of combs positioned in parallel relation; spacing members for spacing said combs apart; a threaded member formed in each of the outermost of said combs; and means

threaded into said threaded members and projecting through the inner positioned combs for retaining the same in position.

10 In testimony whereof I have signed the foregoing specification.

LOUIS BUSHMAN.
